UNITED STATES PATENT OFFICE

1,924,150

HOSE NOZZLE

James H. Browne, East Liverpool, Ohio

Application July 16, 1931. Serial No. 551,262

1 Claim. (Cl. 240—6.46)

This invention relates to hose nozzles and has relation more particularly to a nozzle of this kind especially designed and adapted for use in connection with gasoline or other pump delivery hoses, and it is an object of the invention to provide a hose with an illuminating means to permit the operator when filling a tank or the like to see clearly the exact amount of fluid the tank contains, thus allowing the operator to accurately 10 and completely fill the tank without spillage.

It is also an object of the invention to provide a nozzle of this kind with an illuminating means whereby the desired application of the hose with respect to the filling opening or vent of a tank 15 can be readily and conveniently effected and more particularly after nightfall, and to provide an illuminating means of this kind which is entirely fireproof.

Another object of the invention is to provide 20 means for illuminating the nozzle of a gasoline or other pump delivery hose whereby sales will be increased through ability to determine when a tank is really full and to also result in increased sales through customer satisfaction in avoiding 25 spillage and loss.

The invention consists in the details of construction and in the combination and arrangement of the several parts of my improved hose nozzle whereby certain important advantages are 30 attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

40 Figure 1 is a view in perspective illustrating a nozzle for a gasoline or pump delivery hose constructed in accordance with an embodiment of my invention;

Figure 2 is a view in elevation of the delivery 45 end of the nozzle as herein disclosed;

Figure 3 is a fragmentary longitudinal sectional view taken through the delivery end portion of the nozzle with parts in elevation.

As disclosed in the accompanying drawing, N 50 denotes a nozzle for gasoline or other pump delivery hoses which, in the main, is of a conventional construction or design but which has formed at its delivery end portion an elongated tubular housing 1 open at opposite ends and disposed in a direction lengthwise of the nozzle N.

The forward end of this housing 1 terminates substantially flush with the outer or discharge end of the nozzle N and snugly engaged within the housing 1 is one or more dry batteries 2 of a conventional type, such as employed in connection 60 with flashlights now generally on the market.

Threaded in the opposite end portions of the housing 1 are the annular members or sleeves 3 and 4, the forward member or sleeve 3 being provided with an inwardly disposed flange 5 for contact from without with a conventional glass bull's eye 6 which is held in close engagement with a reflector 7. As is well known, there is arranged inwardly of the applied bull's eye glass 6 and within the reflector 7 a conventional bulb in 70 proper electrical connection with the battery or batteries 2 and, in the present embodiment of my invention, the operating circuit for such bulb or illuminating unit is under control of a conventional switch mechanism including an operating 75 arm 8 extending rearwardly out through the rear open end of the housing 1.

Interposed between the applied rear member or sleeve 4 and the adjacent end of a battery 2 is an expandable member or coil spring 9 operating to maintain the battery or batteries 2 and the other parts of the potential illuminating means in proper effective assembly. As the particular or specific details of the battery or batteries, the bulb or illuminating unit and other directly associated parts of the illuminating means in their construction form no particular part of the present invention, a detailed description and illustration thereof is believed to be unnecessary.

With the operating circuit for the illuminating 90 means closed it is believed to be apparent that a beam of light will be projected forwardly from the housing 1 in advance of the discharge or delivery end of the nozzle N and thereby providing an effective illumination whereby an operator 95 may readily insert the nozzle within the filling opening of a tank and will also provide means whereby the operator can effectively determine whether or not the tank is properly filled.

With the circuit for this illuminating means 100 closed it is also believed to be apparent that in the use of the nozzle spillage and other loss will be effectively avoided.

The mounting and assembly of the annular member or sleeve 3 of the glass 6 is such as to 105 prevent gasoline or the like from reaching the battery 2.

From the foregoing description it is thought to be obvious that a hose nozzle constructed in accordance with my invention is particularly well 110

adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

As a new article of manufacture, a hose nozzle

provided with a housing disposed lengthwise and exterior thereof and terminating substantially flush with the discharge end of the nozzle, said housing being integral with the nozzle and open at opposite ends, a lamp positioned within the housing closely adjacent to its forward end, a battery for said lamp arranged within the housing rearwardly of the lamp, and a switch interposed in the operating circuit between the lamp and battery accessible through the inner open end of the housing.

JAMES H. BROWNE.
